INVALID BED

John G. Cunningham, Spokane, Wash.; R. Hosken Damon and The Old National Bank & Union Trust Co., executors of John G. Cunningham, deceased.

Application December 21, 1936, Serial No. 116,939

2 Claims. (Cl. 5—61)

My invention relates to improvements in invalid beds of the type employed as invalid turners, wherein a section of the bed, or supporting frame for the patient, is mounted on longitudinally extending pivots, so that the pivoted section or frame, containing the patient, is capable of being turned either partially or completely over and secured in adjusted position. By these 10 adjustments of the pivoted frame, the operations of the surgeon and attentions of the nurse are facilitated, and the convenience, comfort, and relief of the patient are enhanced.

In carrying out my invention I provide this type of bed with improved features involving rigid 15 or non-flexible, as well as flexible, cross slats, with adjustable mountings on the rotatable frame or section, in order that different postures of the body of the patient may conveniently be assumed and retained, when required, and under varying 20 conditions; and when, in particular, surgery is to be applied to the spinal column of the patient. The invention also contemplates other improved 25 features by means of which the functions of this type of bed are performed, all as will hereinafter be more fully pointed out and claimed.

In the accompanying drawings I have illustrated one complete example of the physical embodiment of my invention wherein the parts are combined and arranged according to one 30 mode I have thus far devised for the practical application of the principles of my invention, but it will be understood that changes and alterations may be made in these exemplifying structures, within the scope of my claims, without 35 departing from the principles of my invention.

Figure 1 is a side view in elevation of a bed equipped with the improvements of my invention.

Figure 2 is a end elevation at the head of the bed, showing by dotted lines the movement of the 40 pivoted frame, and also the use of the cross slats of the frame.

Figure 3 is a sectional detail view at line 3—3 of Figure 2 showing the operating means for the rotatable frame or invalid turner.

Figure 4 is a detail sectional view at line 4—4 of Figure 1 showing the pinned pivot-bearing at the foot of the bed.

Figure 5 is a plan view of part of the rotatable frame with its flexible cross-slats.

Figure 6 is a detail view showing the mounting cr mount for one end of an anchoring arch-bar, two of which arch-bars are employed on the frame to anchor opposite ends of cross slats.

Figure 7 is a detail sectional view at line 7—7

of Figure 6 showing the adjustable mount for one end of an anchoring arch-bar.

Figure 8 is a sectional view at line 8—8 of Figure 5 showing an under-slung flexible cross-slat. Figure 9 is a sectional view of the frame showing an overhung flexible cross slat anchored at its opposite ends to a pair of arch bars. Figure 10 is a sectional view of the frame showing the use of an over-hung non-flexible or rigid cross-slat anchored at its ends to a pair of arch bars.

In the preferred form of my invention I have utilized a tubular metal bedstead comprising the head-frame 1 and foot-frame 2 with the rigidly joined side bars 3, and the bedstead is provided with usual casters 4. The posts of the head-frame and of the foot-frame preferably converge, as at 5, above these frames, to provide bearing supports for the patient-turner, invalid-turner, or rotatable frame, which is thus conveniently elevated, and readily accessible, for surgical operations and for attentions to the patient.

The rotatable frame, which is of rectangular shape and tubular construction comprises a pair of side rails 6, 6 and complementary end rails 7, 7 and the frame is fashioned with longitudinally extending trunnions 8, 8' at its opposite ends. The trunnion 8' at the foot of the bed is mounted in a U-bearing 9 rigid with the converging posts of the foot-frame, and this trunnion or pivot pin may be locked against turning in its bearing by the use of a pin 10 passed transversely through the U-bearing and the trunnion, both members being perforated for the reception of the pin. When the pin is withdrawn, the frame may readily be rotated, and the withdrawal of the pin readily permits removal of the frame, when the opposite ends of the frame are also free for removal.

The trunnion 8 at the head of the bed is fashioned with an angular extension or shank 11 which is fitted in a complementary hub-socket of a worm-wheel 12, and the latter is journaled in bearings 13 of a housing 14 which forms a rigid cap for the converging posts 5, 5 of the head-frame of the bed. Within the housing and above the worm-wheel is mounted a worm or screw bar 15 having a crank handle 16 exterior of the housing, and it will readily be apparent that the rotatable frame, when pin 10 is removed, may be turned by manipulating the crank 16, and the meshing of the worm-teeth with the worm-wheel 12 will hold the rotated frame in adjusted position, in conjoint use with pin 10.

I have illustrated three types of cross-slats, or rather three uses of two types of cross-slats, with the patient turner or frame, the cross-slats 17 be-

ing flexible and fashioned of canvas or other similar material, and the cross slat 19 being non-flexible, or rigid, or resilient, as the case may be, and the cross slats 19 may be fashioned of resilient steel plates or of rigid steel plates.

5 The flexible straps 17 may be underslung with relation to the frame, as in Figure 8, or over-hung with relation to the frame as indicated in Figure 9, but in both instances the cross slats are fastened to the side rails 6 of the frame by buckled straps 18 or similar detachable fastenings, provided at the opposite ends of the cross slats.

10 The rigid or resilient cross slats, 19, as indicated in Figure 10 are preferably overhung with relation to the frame, and these metal plates are fashioned with end hooks 20 that are detachably fastened on special mounts or mounting devices which are adjustable on the respective parallel side rails 6,6 of the frame.

15 20 As best seen in Figure 1, each of the side rails 6 is provided with a longitudinally extending series of spaced holes 21 that extend horizontally and transversely through the tubular rails, and these holes are employed in mounting on the 25 side rails a pair of anchoring arch-bars 22 of semi-rigid or resilient metal, which arch bars extend longitudinally of the rails.

20 30 At each end of each arch-bar is carried a perforated fastening yoke 23 of U-shape, which straddles the side rail of the frame for support of the arch-bar. These yokes have holes or perforations that will register with the holes 21 of the side rails, and pins 24 are passed through the perforated yokes and rails to hold the yokes in adjusted position.

35 Each yoke is fashioned with a pair of upright, perforated, ears 25 in which are mounted bolts 26, and as best seen in Figure 6, the metal arch-bars 22, at their ends are curled inwardly to form sleeves 27 that encircle these bolts and firmly support the arch bars above and between the supporting yokes.

40 45 As indicated in Figure 1 the curvature of these arch-bars may be changed to raise, or to lower, the bars, and these bars thus become adjustable anchors for the opposite ends of the cross slats. Either one, or both, of the end-yokes of an arch-bar may be adjusted along the rail 6, toward or

from the foot of the bed, or toward and from the head of the bed. By adjusting the distance between the yokes of each pair, the vertical position, or height of the arch bars is varied, and accordingly the vertical position of the anchored cross-slats, which are mounted on the arch-bars, is varied. These variations in the curvature of the arch-bars are carried to the cross-slats anchored thereon, and it will readily be apparent that cross-slats may thus be adjusted to fit 10 curvatures of the body of the patient.

15 By use of the overhung cross-slats in Figures 9 and 10 the portion of the patient's body supported thereby may be elevated above another portion of the body that is supported by the underslung cross-slat of Figure 8, in order to facilitate surgical operations, or nursing attentions, and also for convenience and relief of the patient.

20 Having thus fully described my invention, what I claim as new and desire to secure by Letters Patent is:

1. In an invalid bed having head and foot frames, the combination with a rotatable and removable patient-turner-frame having an end trunnion, of a bearing in the foot frame for said 25 trunnion and detachable means for preventing rotary movement of the trunnion in its bearing, a housing forming a cap on the head-frame, a worm-wheel journaled in the housing and having an angular hub-socket, a second trunnion on the 30 patient-turner-frame slidably fitted in said socket, a worm journaled in the housing for co-action with the worm-wheel, and a crank for turning the worm.

2. In an invalid bed having head and foot 35 frames, the combination with a patient-turner-frame having an end trunnion, of a U-shaped bearing on the foot-frame, a removable pin engaging holes in said bearing and trunnion, a bearing-housing mounted on the head frame, a worm-wheel having an angular hub-socket and mounted in the housing, a second trunnion rigid with the patient-turner-frame and slidably fitted in said 40 socket, a worm journaled in the housing for co-action with the worm-wheel, and a crank for turning the worm.

JOHN G. CUNNINGHAM.
